UNITED STATES PATENT OFFICE.

HENRY BAMBERGER, OF PHILADELPHIA, PENNSYLVANIA.

DESIGN FOR A CHILD'S CAP.

SPECIFICATION forming part of Design No. 17,254, dated April 12, 1887.

Application filed March 15, 1887. Serial No. 225,195. Term of patent 7 years.

To all whom it may concern:

Be it known that I, HENRY BAMBERGER, a citizen of the United States, residing in Philadelphia, Pennsylvania, have invented a new and original Design for a Child's Cap, of which the following is a specification.

My design for a child's cap is fully shown in the accompanying drawing; and it consists, essentially, of a lower back portion, B, with an upper full-crown piece, D, showing gathers at the point *a*, where it joins the lower back portion, B.

The design of the body A and trimming can be varied as desired, these portions forming no part of my invention.

I claim—

The design for a child's cap, the same consisting of a cap having a lower back portion, B, with an upper full crown, D, showing gathers at the point *a*, where it meets the back portion, substantially as shown and described.

In testimony whereof I have signed my name to this specification in the presence of two subscribing witnesses:

HENRY BAMBERGER.
